A. A. ADAMS.
REGULATING DEVICE FOR BEATER ROLLS.
APPLICATION FILED MAR. 7, 1917.

1,277,350.

Fig. 1

Fig. 2.

Patented Sept. 3, 1918.

The drawing illustrates a mechanical assembly, possibly a flywheel or motor. It features a vertical shaft (14) with a flywheel (15) at the top. A horizontal shaft (24) is connected to the flywheel. Various components are labeled with numbers: 16, 17, 18, 19, 20, 21, 22, 23, 24, 25, 26, 27, 28, 29, 30, 31, 32, and 34. The right side of the drawing is labeled 'Fig. 4.' and shows a detailed view of a part of the assembly, including a gear (20) and a shaft (25). The entire drawing is enclosed in a rectangular border.

UNITED STATES PATENT OFFICE.

ARCHIBALD A. ADAMS, OF SOUTH BREWER, MAINE, ASSIGNOR TO EASTERN MANUFACTURING COMPANY, OF BANGOR, MAINE, A CORPORATION OF MAINE.

REGULATING DEVICE FOR BEATER-ROLLS.

1,277,350.

Specification of Letters Patent.

Patented Sept. 3, 1918.

Application filed March 7, 1917. Serial No. 153,036.

To all whom it may concern:

Be it known that I, ARCHIBALD A. ADAMS, a citizen of the United States, residing at South Brewer, in the county of Penobscot 5 and State of Maine, have invented new and useful Improvements in Regulating Devices for Beater-Rolls, of which the following is a specification.

This invention relates to pulp-beating machines that are used in the manufacture of paper. The pulp is beaten in a tub by two coöperative elements, one of which is commonly termed a "beater-roll" and the other of which is commonly termed a "bed-plate." The bed-plate is arranged substantially flush with the bottom of the beater-tub and the beater-roll is adjustable toward and from the bed-plate. As the pulp undergoes the beating process the coaction of the peripheral blades on the beater-roll and the blades on the bed-plate reduces the lumps of stock, and the space between the beater-roll and bed-plate must be diminished from time to time as the lumps of stock are reduced, to 15 disintegrate the fibers gradually. For this purpose it is customary to adjust the beater-roll bodily toward the bed-plate by moving the journals in which the shaft of the beater-roll has its bearings. The increments of adjustment movement are necessarily fine and must be gaged with great accuracy. Heretofore, apparatus of the character above described has not been provided with any means for indicating the degree or degrees 20 of such adjusting movement, and the latter has been dependent upon the skill and experience of the attendant who makes the adjustment.

My present invention provides an indicator and operating mechanism therefor in combination with the mechanism by which the aforesaid adjusting movements of the beater-roll are effected. Such indicator is adapted to afford a visual indication from 25 which the attendant may observe how much space separates the beater-roll from the bed-plate, and by which he may be informed, when effecting an adjustment, how much adjusting movement has been effected. One 30 advantage of such combination is that the attendant, having specific instructions to effect an adjustment of a prescribed number of units of movement may carry out such instructions with accuracy under the guidance of the indicator, and no skill or expe-

rience in the art of preparing pulp, or in the manipulation of the adjusting mechanism, is required in such cases.

The indicator that I prefer to use for the purpose stated would have a series of wheels 60 rotatable in opposite directions and each bearing a series of indicating symbols, the capacity of such indicating wheels to rotate in opposite directions enabling the attendant to gage the retractive movement of the 65 beater-roll from the bed-plate as well as the movement of such roll toward the bed-plate. Thus the initial adjustment of the beater-roll and bed-plate may be determined according to the initial size of the lumps in 70 the paper stock. The mechanism of the well-known Veeder counter or odometer is suitable for my purpose and I have illustrated an indicator embodying such construction.

75

Of the accompanying drawings:—

Figure 1 represents a longitudinal vertical section of the beater-tub of well-known construction, including a beater-roll, bed-plate, "back-fall," and "midfeather."

80

Fig. 2 represents a side elevation, on a larger scale, of a portion of said tub, and includes mechanism for adjusting the beater-roll.

Fig. 3 represents a top plan view, on a 85 larger scale than Fig. 2, of the indicator that is included in Fig. 2.

Fig. 4 represents an end elevation of the adjusting mechanism and indicator included in Fig. 2, the direction of view being from 90 right to left.

The same reference characters indicate the same parts wherever they occur.

The beater-tub indicated at 10 is provided with a midfeather 11 and with a back-fall 95 12. The bed-plate indicated at 13 is of well-known construction, and is embedded in the bottom of the tub so that its blades will not unduly impede the flow of the stock. The beater-roll indicated at 14 is also of well-known construction. It is carried by a shaft 15 and may be driven by any suitable means in the direction indicated by the arrow, to coöperate with the bed-plate in disintegrating the fibrous lumps of paper stock, and to 100 105 propel the contents of the tub over the back-fall 12 and around the midfeather according to well-known practice.

The bearings for the shaft 15 of the beater-roll are indicated at 16, 16, and 110

the present instance said bearings are carried by a pair of bars 17, 17. One end of each bar rests upon a fixed support such as that indicated at 18 in Fig. 2, and the other end is connected by a pivot pin 19 to a screw rod 20. The rods 20, 20 extend upwardly and have screw-threaded engagement with nuts 21, 21. These nuts rest upon and are rotatable relatively to stationary supports

10 22, 22.

Mechanism is provided for rotating the nuts 21, 21 in unison, to raise or lower the bearings 16, 16 in unison. For this purpose each nut is provided with a bevel gear portion 23. An operating shaft 24 is provided with pinions 25, 25, and these pinions coact respectively with the gear portions 23. A hand-wheel 26 is affixed to shaft 24.

As the hand-wheel is turned in one direction or in the opposite direction the nuts 21 will be rotated and the beater-roll will be adjusted toward or from the bed-plate. The degree of adjusting movement of the beater-roll is relatively fine in proportion to the degree of rotary movement of the hand-wheel, the reduction being due for the most part to the screw-thread connection between the nuts 21 and rods 20 and being multiplied by the bevel gears and also by the lever effect of the bars 17.

The indicator is indicated as a whole at 30. It is mounted upon a suitable fixture 31, and its shaft 32 is provided with a sprocket-wheel 33. A chain 34 runs over sprocket-wheel 33 and also over a driving sprocket-wheel 35, the latter being affixed to shaft 24. The indicator includes a series of indicating wheels, in the present instance, four, and they are shown at *a*, *b*, *c*, and *d*. Inasmuch as the indicator embodies the con-

struction of the well-known Veeder counter it will not be necessary to illustrate its structural details but it will be sufficient to state that each wheel bears ten indicating symbols, comprising the scale of numerals 45 0 to 9. In such counters the symbols of the first indicating wheel usually represent tenths of units, while those of the second, third and fourth wheels represent respectively units, tens of units, and hundreds of 50 units. In the present instance the ratio of gearing is such that one step of wheel *a* represents an adjusting movement of one one-thousandth of an inch of the beater-roll toward and from the bed-plate. 55

I claim:

1. The combination with the beater-roll and bed-plate of a pulp-beating machine, of means arranged to adjust said beater-roll toward and from said bed-plate, and means, 60 including a visual reversible indicator, arranged to be operated by said adjusting means to count and indicate increments of movement, of predetermined length, of said beater-roll toward and from said bed-plate. 65

2. The combination with the beater-roll and bed-plate of a pulp-beating machine, of means arranged to adjust said beater-roll toward and from said bed-plate, a counting device having indicating means adapted to count units of movement and indicate the number of such units and means arranged to be operated by said adjusting means to operate said counting device. 70

In testimony whereof I have affixed my signature.

ARCHIBALD A. ADAMS.

Witness:

S. B. COPELAND.
